UNITED STATES PATENT OFFICE.

JOHAN KARLSEN MÖYSTAD, OF CHRISTIANIA, NORWAY.

FUEL-INJECTING APPARATUS FOR INTERNAL-COMBUSTION ENGINES.

1,388,588.

Specification of Letters Patent. Patented Aug. 23, 1921.

Application filed July 24, 1917. Serial No. 182,449.

To all whom it may concern:

Be it known that I, JOHAN KARLSEN MÖYSTAD, a subject of the King of Norway, and residing at Ovre Foss 14, Christiania, Norway, have invented certain new and useful Improvements in Fuel-Injecting Apparatus for Internal-Combustion Engines, of which the following is a specification.

This invention relates to the injection of fuel into the working cylinders of internal combustion engines by means of a high pressure air compressor, the air directly acting upon and opening the fuel supply valve which permits the fuel from the supply which is stored on the front side of the valve to pass to the engine.

The invention consists in an improved arrangement of the fuel supply valve according to which the valve is placed in the cylinder head and at a certain distance from the fuel injector inlet, the said valve being adapted to close and open the supply channel which is common to the compressed air and the fuel, in such a manner that the mixture does not pass through and around the valve.

The accompanying drawing illustrates one example of the invention, in which the compressed air is supplied by means of a two-stage high pressure air compressor.

Figure 1 is a section through the compressor and the combined valve for the mixture of compressed air and fuel, the compressor piston being shown in its lowest position.

Fig. 2 is a similar view, the compressor piston being shown in its highest position.

The compressor is driven in any known manner from the engine driving shaft by means which are not shown or from a counter shaft which is separately driven from the above named main shaft. The compressor is shown in the drawing as a two-stage compressor and is provided with a differential piston, an intermediate pressure chamber and a separate suction valve for atmospheric air in the high pressure cylinder.

1 indicates the low pressure piston and 2 the low pressure cylinder provided with the suction inlet 3 and the outlet 4. Through the valve 6 passes the air compressed under low pressure, to the intermediate receiving chamber 5, from whence it passes to the high pressure cylinder 8 above the piston 7 at the end of the stroke. 9 is a valve acted upon by a spring, through which valve at-

mospheric air is supplied to the high pressure compressor at the down-stroke of the piston, the compressor thereby receiving an additional supply of air. At the upward stroke of the compressor, the compressed air charge passes along the duct 10 into which is led the fuel supply duct 16, through which fuel is supplied under sufficient pressure to be forced into the conduit 65 or duct 10 against the pressure of the compressed air therein, so that the latter part of such duct 10 receives the mixture of fuel and air. 13 is the injector channel by which the mixture passes into the working cylinder, and communication between the duct 10 and the channel 13 is controlled by the fuel inlet valve 12. As shown the valve member is hollow to accommodate a valve spring 14 and by means of an adjusting screw 15 the valve spring is given such a tension that it will open on the power stroke of the compressor at any desired degree of pressure, whereby the fuel mixture will be injected at the right moment to precisely regulate the time of combustion. The valve 12 is arranged in the cylinder head and spaced a short distance from the injector inlet so that it will not be exposed to the heat in the cylinder and its reciprocating motion hindered by un-burned substances which may be thrown down by the mixture of air and fuel.

By thus arranging the valve the mixture passes it by and does not go around or through it.

Having now described my invention, what I claim as new and desire to secure by Letters Patent is:—

1. In a fuel injector for engines, an air compressor having an outlet conduit, a valve seating and housing formed co-axially with said conduit, a cylindrical valve mounted as a sliding fit in such housing and normally closing said conduit, the head of said valve being directly operated upon by compressed air for opening said conduit, a fuel supply inlet communicating with said conduit between the air compressor and valve housing and an outlet for air and fuel normally closed by said valve, such that the air and fuel are deflected to a minimum extent and pass exteriorly of the valve body and valve seating.

2. In a fuel injector for engines, an air compressor having an outlet conduit, a valve seating and housing formed co-axially with

said conduit, a cylindrical valve mounted as a sliding fit in such housing and normally closing said conduit, the head of said valve being directly operated upon by compressed air for opening said conduit, a spring for normally holding said valve closed, means for varying the tension of said spring, a fuel supply inlet communicating with said conduit between the air compressor and 5 valve housing and an outlet for air and fuel normally closed by such valve such that the air and fuel are deflected to a minimum extent and pass exteriorly of the valve body and valve seating.

10 3. In a fuel injector for internal combustion engines, an air compressor having an elongated outlet passage communicating at one end with a valve chamber which is co-axial with the passage, a valve arranged 15 in the chamber and having a head normally closing communication between the passage and chamber and directly acted upon by air in the outlet passage for opening the valve, a fuel inlet communicating with the passage 20 between the compressor and valve chamber,

25

an air and fuel outlet communicating with the valve chamber and normally closed by said valve, a spring in the chamber for normally closing the valve, and means for varying the tension of said spring.

30

4. In a fuel injector for engines, an air compressor having an outlet conduit, a valve seating and housing formed co-axially with said conduit, a cylindrical valve mounted as a sliding fit in such housing, and normally closing said conduit, the head of said valve being directly operated upon by compressed air for opening said conduit, a fuel supply inlet communicating with the said conduit between the air compressor and valve housing, adjustable yielding means for normally holding the valve in closed position, and an outlet for air and fuel normally closed by said valve, such that the air and fuel are deflected to a minimum extent and pass exteriorly of the valve body and valve seating.
